FILE SHARPENING MACHINE

Alvin H. Swartzwelder, Santa Monica, Calif.

Application May 5, 1944, Serial No. 534,303

3 Claims. (Cl. 51—33)

The present invention relates to new and useful improvements in file sharpening machines, and has for one of its important objects to provide, in a manner as hereinafter set forth, a power driven device of this character which may be readily carried from place to place.

Another very important object of the invention is to provide a portable, power driven machine of the character which may be expeditiously and accurately adjusted to sharpen different sizes of files.

Still another very important object of the invention is to provide a file sharpening machine of the character described which embodies unique feed means.

Other objects of the invention are to provide a portable, power driven file sharpening machine which will be comparatively simple in construction, strong, durable, highly efficient and reliable in use, compact and which may be manufactured at low cost. All of the foregoing, and still further objects and advantages of the invention, will become apparent from a study of the following specification, taken in connection with the accompanying drawings wherein like characters of reference designate corresponding parts throughout the several views, and wherein:

Figure 1 is a view in side elevation, showing a file sharpening machine constructed in accordance with the present invention in use.

Figure 2 is a top plan view thereof.

Figure 3 is a view in horizontal section, taken substantially on the line 3—3 of Figure 1.

Figure 4 is a longitudinal sectional view, taken substantially on the line 4—4 of Figure 2.

Figure 5 is a view in transverse section through the front portion of the device with the electric motor omitted.

Figure 6 is a detail view in longitudinal section through one of the adjustable guide screws.

Referring now to the drawings in detail, it will be seen that reference character 1 designates a rail or base of substantially T-shaped cross section. The rail 1 is provided, beneath its end portions, with transverse feet 2. The rail 1 is adapted to receive longitudinally thereon the file 3 to be sharpened. A stop 4 on the rear end of the rail 1 abuts the corresponding end of the file 3.

Operable on the file 3 and the rail 1 is a carriage which is designated generally by reference character 5. The carriage 5 includes a horizontal base 6 of substantially the shape shown to advantage in Figure 3 of the drawings. The base 6 has formed therein a substantially T-shaped, longitudinal groove or channel 7 (see Fig. 5) which slidably accommodates the file 3 and the

head of the rail 1. Guide screws 8 are threadedly mounted for adjustment in the side portions of the base 6 for engagement with the longitudinal side edges of the file 3. Lock nuts 9 secure the screws 8 in adjusted position.

Rising from the rear end of the base 6 is a flange 10. The flange 10 is provided with an opening which slidably accommodates a bar 11. The bar 11 is provided, on its rear end, with a fork or yoke 12 in which a dog 13 is journaled for engagement with the teeth of the file 3. A spring 14 yieldingly engages the dog 13 with the file 3. Fixed on the sides of the yoke 12 and projecting forwardly therefrom are arms 15 the purpose of which will be presently set forth. A coil spring 16 yieldingly urges the bar 11 forwardly in the flange 10. An upstanding stop 17 is provided on the base 6 for the bar 11.

Rising from the forward portion of the base 6 is a spindle 18. A substantially rectangular bearing 19 is journaled for rotation on the spindle 18. Slidable on the base 6 and the bearing 19 is a plate 20. The plate 20 has formed therein a longitudinal opening 21 which slidably accommodates the bearing 19. Coil springs 22 are provided between the bearing 19 and the forward end of the opening 21 for yieldingly urging the plate 20 forwardly on the base 6. An integral bar 23 traverses the opening 21 rearwardly of the bearing 19. A screw 24 is threadedly mounted in the bar 23 and engaged with the bearing 19 for adjusting the plate 20 relative to the spindle 18. The plate 20 is formed to provide a pair of rearwardly facing shoulders or abutments 25 for engagement with the forward ends of the arms 15.

Rising from the forward portion of the plate 20, on opposite sides of the opening 21, is a pair of standards 26. An electric motor 27 is mounted for vertical swinging adjustment between the standards 26. The motor 27 is provided with a suitable control switch 28. Mounted on the shaft 29 of the motor 27 is a beveled grinding wheel 30 of suitable material, preferably carborundum.

Extending rearwardly from the standards 26 is a yoke 31. An operating handle 32 is fixed on the yoke 31. A conductor cord 33 for connection with any suitable source of current supply passes through the handle 32 to the motor 27.

Pivotedly mounted beneath the base 6 is a dog 34 for engagement with the file 3 for positively preventing retrograde movement of the machine thereon. A coil spring 35 yieldingly engages the dog 34 with the file 3. Mounted beneath the forward end portion of the base 6 is a pair of leaf

springs 36 for engagement beneath relatively thin files for stabilizing the device thereon.

It is thought that the operation of the machine will be readily apparent from a consideration of the foregoing. Briefly, with the carborundum wheel 30 turning at the desired speed, said wheel, through the medium of the handle 32, is swung in an arc across the face of the tooth of the file 3 which is being sharpened. When the operation has been completed the wheel 30 is swung clear of the file and one of the shoulders 25 is engaged with the opposed forward end of the adjacent arm 15 for feeding the assembly forwardly to the correct position for sharpening the next tooth. This is effected by the engagement of dog 13 and an associated file tooth, the pressure on one of members 15 effected by the shoulder 25 serving to move the carriage 5 and its associated mechanism forwardly with respect to the position of the dog 13, until the dog 34 has ratcheted over the next adjacent tooth. When the handle is again swung toward a central position, releasing the pressure of member 15, dog 34 holds the device against retrograde movement and the spring 16 causes the dog 13 to ratchet over and engage behind the next adjacent tooth. The operation is then repeated. When the assembly is fed forwardly as above described, it is secured against retrograde movement by the dog 34 while the spring 16 moves the dog 13 forwardly for engagement with the next tooth of the file. Through the medium of the screw 24 the wheel 30 may be adjusted toward or away from the spindle 18. Thus, the arc described by the wheel 30 about the spindle 18 may be controlled or regulated as desired for files having teeth of different degrees of curvature. This also adjusts the shoulders 25 relative to the arms 15 for regulating the length of each step of the forward feed of the assembly, it being apparent that the greater the distance of shoulders 25 from the ends of arms 15, the less distance carriage 5 will travel when the handle 13 is swung through its maximum path. Obviously, the less the radius of each tooth for a file of a given width, the greater the linear distance the carriage 5 must travel to be properly positioned for grinding the next tooth. A retaining nut and washer 37 and 38, respectively, are provided on the spindle 18 for the members 19, 50

20, etc. The adjustable guide screws 8 permit the base 6 to be readily mounted for operation on different widths of files. Spring pressed balls 39 are mounted in the inner end portions of the 5 guide screws 8 and ride on the longitudinal edges of the file 3 for compensating for any slight irregularities therein.

It is believed that the many advantages of a 10 file sharpening machine constructed in accordance with the present invention will be readily understood, and although a preferred embodiment of the device is as illustrated and described, it is to be understood that changes in the details of construction and in the combination and arrangement of parts may be resorted to which 15 will fall within the scope of the invention as claimed.

What is claimed is:

1. A file sharpening machine comprising a rail 20 for receiving thereon a file to be sharpened, a carriage slidable on the file and the rail, a manually operable support mounted for swinging movement on the carriage, a grinding wheel mounted on said support, and means engageable 25 with the teeth of the file and operable by the support for feeding the carriage longitudinally relative to said file.
2. A file sharpening machine comprising a rail 30 for receiving thereon a file to be sharpened, a carriage movable longitudinally on the file and the rail, said carriage including a base, a plate mounted for rotation on said base, an electric motor mounted for vertical swinging adjustment on said plate, a grinding wheel operatively connected to said motor, and means on the base operable by the plate and engageable with the file for shifting the carriage longitudinally relative to said file.
3. A file sharpening machine comprising a base 40 movable longitudinally on a file to be sharpened, a vertical spindle on the base, a bearing journaled on said spindle, a plate slidable on the bearing and the base, means for adjusting the plate relative to the spindle, means for rotating the plate 45 about the spindle, a grinding wheel mounted on the plate, and means operable by the plate and engageable with the file for moving the base longitudinally on said file.

ALVIN H. SWARTZWELDER.
